[57] CLAIM

The ornamental design for a container for food products or the like, substantially as shown.

DESCRIPTION

FIG. 1 is a side elevational view of a container for food products or the like showing our new design, the view from each side taken at 90° intervals being identical; FIG. 2 is a sectional view taken on the line 2—2 of FIG. 4;

FIG. 3 is a bottom plan view; and
FIG. 4 is a top plan view thereof.

FIG.3
